UNITED STATES PATENT OFFICE.

LÉON EMILE RÉMONDY, OF PARIS, FRANCE.

MECHANICALLY-OPERATING RETARDING DEVICE FOR PROJECTILE FUSES AND OTHER FIRING DEVICES.

Application filed May 17, 1926, Serial No. 109,768, and in France July 11, 1925.

It is known that projectile fuses all comprise a firing mechanism having a striker and a percussion cap, one member at least of which is movable, firing or ignition resulting from the impact between these two members. The impact between the striker and the percussion cap must be capable of being retarded and even, in certain cases, being prevented from taking place in order to avoid any premature or untimely operation, or else in order that the operation can only take place at the end of a predetermined duration of flight. It may also be desired to render any operation impossible beyond a predetermined distance travelled by the projectile.

Further, the firing of the charge of the projectile must be capable in certain cases of being retarded, that is to say capable of being arranged so that it does not immediately follow the ignition of the percussion cap. In order to retard the firing of the charge after the ignition of the percussion cap use is most usually made of pyrotechnical devices. In order to safeguard against premature or untimely operations use is most generally made of mechanical devices combined if desired with pyrotechnical devices.

The present invention relates to a mechanically operating retarding or nullifying device, more particularly adapted for use with projectile fuses. The new device is essentially characterised by a crown of balls which may if desired be placed in a cage and which are placed between two convergent bearing surfaces one at least of which is formed upon the member to be displaced, such as a striker or a percussion cap, for example. One of the bearing surfaces for the balls is, in any case, provided upon a member adapted to make a movement of rotation under the effect of the action of the air, for example. The balls form wedges between their bearing surfaces, being driven between these surfaces by their own weight which may be increased by an additional rigid or elastic load.

The member to be displaced, thus wedged or locked by the balls can only advance by means of a helical movement of very small pitch, resulting from the combined rotation and advancing movement of the balls between their bearing surfaces, which forward movement of the balls cannot itself take

place without a longitudinal push combined with the movement of rotation of at least one of the bearing surfaces.

The invention further comprises a series of additional safety devices which may be employed in combination with the ball retarding device or any other screw action retarding device.

Various practical examples of utilization and construction of the invention are illustrated in the accompanying drawings, in which:

Figure 1 shows in longitudinal sectional elevation the use of the invention for retarding the operation of the firing mechanism of a percussion fuse.

Fig. 2 is a sectional view illustrating the mechanism, shown in Fig. 1, in firing position;

Figs. 3 and 4 are sectional views illustrating a second embodiment of the present invention, the parts being shown in their normal position and in firing position, respectively;

Figs. 5, 6 and 7 are longitudinal sectional views illustrating another embodiment of the present invention;

Figs. 8, 9 and 10 illustrate, in longitudinal sectional views, other embodiments of the present invention;

Fig. 11 is a partial sectional view illustrating one embodiment of the present invention wherein the percusion cap holder carries a movably mounted percusion cap.

Referring more particularly to Figure 1, A is a fuse body, shown in part, in a suitable cavity of which is located a fixed percusion cap B, firing being produced by the impact between this fixed percusion cap and a movable striker C. The retarding device comprises, according to the invention, a crown of balls D, normally wedged between the wall e of the enlarged space or chamber E formed in the fuse body and a frusto conical bearing surface c formed upon the striker C.

The striker is arranged so as to be adapted to turn in the lodgment or enlarged space E under the action, for example, of the pressure of the air exerted upon an air screw F secured upon an extending portion C¹ of the striker carrying rod. The balls B are normally pressed between the surfaces c and e, being held in place by the action of a spring

G pressing at one end upon an interposed disc g and at the other upon a shoulder C² of the striker C.

The forward movement of the striker 5 towards the percussion cap B can only take place under the action resulting from a rotation and a push such as those which would be due to the movement of the projectile as it progresses in its flight in the air, and the 10 forward movement of the striker will also result from the combined rotation and forward movement of the crown of balls D which take up, between the bearing surfaces e, c a helical movement of small pitch.

15 It is possible by this means to retard the arrival of the striker into a cocked position. In this first example the retarding device may be retained until the moment when the projectile has travelled over a 20 suitable distance, the slow advance of the striker having then brought the balls D opposite a widened portion E¹ of the lodgment E where these members cease to bear simultaneously upon the surface c and an adjacent 25 complementary surface.

The striker will then be definitely cocked, that is to say, ready to move so as to strike the percussion cap under the effect of an impact against an obstacle. The operation of 30 the cocked striker may be obtained by any known means. A pin H which, in the cocked position, is placed in the neighbourhood of the front face or edge A of the fuse body may, for example, be disposed upon 35 the rod C¹. As the result of an impact this pin will be immediately sheared through, thus allowing the striker to be driven towards the percussion cap B.

With the retarding device described it is 40 difficult for untimely operations to take place, since the forward movement of the striker towards the percussion cap necessitates a combined push and rotation extending over a lengthy period. It will be immediately understood that a simple impact, 45 in other words even a strong push, on condition however that it is not of such a nature as to cause the balls and their bearing surfaces to be crushed, will not allow sufficient advance of the striker to take place.

50 It is also easy to add to the retarding device described, additional safety devices which render an untimely operation impossible even in the event of the failure of the balls D.

Figures 3 and 4 show in longitudinal sectional elevation an example in which the new retarding device is fitted to a percussion fuse for aerial bombs and is combined 60 with a series of additional safety devices.

In this example the balls D instead of being located between a frusto-conical wall formed upon the striker carrier C¹ and the fuse body, are disposed between a similar 65 frusto conical wall c and the cylindrical

wall i of a percussion cap holder I rendered movable in the fuse body A. In this percussion holder will be formed a flare or widened portion i¹ in which the balls D must arrive for the striker to be cocked. 70 The movable percussion cap holder is normally prevented from entering into the fuse body by the pressure of a spring I¹ one end of which presses upon the end of the fuse body. At the other end the percussion cap 75 holder presses upon the plug A¹.

If the fuse was constructed as in the previous example, that is to say without additional external safety devices, in other words if one imagines, in the drawing, that the retaining collar J does not exist, an accidental push, even a very strong one, exerted upon the striker carrier C¹, would not be sufficient to subject the balls D and their bearing surfaces to the action of an excessive force, since it would have the effect of driving in simultaneously the striker and the percussion cap holder maintained in their relative positions by the wedging of the balls, and this driving in would be accompanied by the compression of the spring I¹. The inward movement of the striker carrier would in any case be limited by the boss of the air screw F abutting against the front face or edge of the fuse body before any relative movement had taken place between the striker carrier and the percussion cap holder. In other words any impact upon the projectile before the cocking of the mechanism produced by the combined rotation and the pressure upon the striker carrier cannot produce an operation of the firing mechanism and cannot in addition give rise to an excessive force upon the balls and their bearing surfaces. 105

In practice, in order to adapt the invention for use upon an aerial bomb, a safety device is interposed between the boss F of the air screw and the front face of the fuse body, which safety device is largely formed, 110 in the known manner, for example by two half collars J which a spring tends to force open for their withdrawal, the two ends J¹ of which collar are held together by a claw K which may be disengaged automatically 115 by the fall of the bomb or by the action of a pull exerted by the pilot.

Once this safety device is withdrawn the pressure of the air acting upon the air screw exerts a push and produces at the same time 120 a movement of rotation of the latter the effect of which is to produce an inward movement and a movement of rotation of the striker carrier which describes a helical movement of very small pitch on account 125 of the interposition of the balls D between the bearing surface c upon the striker carrier and the bearing surface i upon the movable percussion cap holder.

If, as it is easy to imagine, the opposing 130

force exerted by the spring I^1 is sufficient to overcome the push exerted by the balls D upon the percussion cap holder, the latter remains fixed and the striker carrier advances relatively to the percussion cap holder. When the balls D reach the enlarged part i^1 the pin H comes into contact with the front edge of the fuse body and the striker is cocked. Any impact against an obstacle after this will cause the pin H to be broken and the striker to be thrown against the percussion cap B , as shown in Figure 4.

Of course, any movement of rotation of the percussion cap holder must be prevented, for example, as shown in the drawing, by a fixed stop A^2 engaging in a slideway i^2 in the said percussion cap holder.

The device described above may be fitted to a time fuse for aerial bombs. Figures 5, 6 and 7 illustrate in longitudinal sectional elevation, in three different positions, such an application of the device.

On account of the provision of a rectilinear guiding of the striker carrier C^1 , obtained for example by means of a stud A^3 attached to the plug A^1 and engaging in a groove c^1 upon the rod C^1 , it is possible to prevent any rotation of the striker from taking place until the latter, starting from the position shown in Figure 5, has travelled over the distance between the stud A^3 and the transverse groove C^3 formed at the end of the said groove i^1 in the rod C^1 and has reached the position shown in Figure 6.

As long as the groove C^3 has not come into coincidence with the stud A^3 the striker will not be able to turn and it will carry along, through the medium of the balls D the movable percussion cap holder I . As a consequence, the movement of rotation of the striker cannot take place, while the continuation of its inward movement is prevented by the end of the groove C^3 abutting against the stud A^3 . As the striker can no longer move forward, the pressure of the spring I^1 combined with the rotation of the striker causes the percussion cap holder I to descend; in other words the percussion cap B and the point of the striker are made to move towards each other.

As soon as the balls D coincide with the enlarged portion i^1 the spring I^1 will be able to act freely and project the percussion cap B against the point of the striker, as shown in Figure 7.

By suitably adjusting the distance to be travelled by the striker before it can make its movement of rotation, the path to be travelled by the percussion cap holder before its enlarged portion i^1 coincides with the balls D and by adjusting the tension of the compression spring I^1 the period of flight of the projectile, at the end of which firing will take place, may be determined.

It is quite clear that modified means may be provided for acting upon any one of the members which retard the operation of the firing mechanism; an action from the outside upon the spring I^1 may be provided for, a device for varying the longitudinal stroke (without rotation) of the striker may be provided or the duration of this travel of the striker may be varied by varying the mass or the shape of the air screw. A series of different air screws which may be fitted alternatively upon the striker carrier may also be provided.

Naturally the fuse described above, which is provided for time operation, may comprise, as it is known in principle, a device for making it operate by percussion when it strikes an obstacle, in the case when the time operation has not taken place before this impact. It will be sufficient, for example, to provide for the possibility of shearing the stud or stop A^3 by violently driving in the striker carrier which has previously reached the cocked position, the balls being released from their support.

In the case of the application of the invention to vertically suspended aerial bombs, a suspension ring F^1 may be provided, as shown in Figs. 5 to 7, upon the boss of the air screw F or this ring may be mounted upon an extended portion of the striker carrier C^1 .

In the examples described, the opposing spring I^1 may be dispensed with if care is taken to make the movable percussion cap holder of sufficient mass. There is even an advantage, in certain cases, in dispensing with this spring, in that it allows the striker and the percussion cap holder to be brought nearer than when the bomb is in the upturned position shown in the figures, which position it only takes up after a certain length of time from the moment when the projectile commences its fall.

The convergence between the bearing surfaces of the balls D may be obtained, as in the examples described above, by forming a frusto-conical surface upon the striker carrier and a cylindrical surface upon the fuse body or upon a movable percussion cap holder. It may on the other hand be obtained by forming the frusto-conical surface upon a movable percussion cap holder, the cylindrical bearing surface being formed upon the striker carrier.

Figure 8 shows in sectional elevation, such a modification.

In this case, as shown in the figure, a part C^4 of the rod C^1 of the striker carrier is turned down to a smaller diameter, which part replaces the widened portion i^1 provided, in the preceding examples in the movable percussion cap holder.

In order to prevent an untimely impact exerting an excessive force upon the balls,

D and their bearing surfaces, use may be made, instead of a movable percussion cap holder carried along longitudinally, of a fixed percussion cap combined with a striker carrier made in two parts. This modification is shown in longitudinal sectional elevation in Figure 9.

In this example the balls D are disposed between a frusto-conical bearing surface e formed in the lodgment E provided in the fuse body A and a cylindrical surface of the rod C¹ of the striker carrier. The rod C¹ comprises, as in the previous example, a turned down portion C⁴. This striker carrying rod proper is adapted to move, by means of studs or pins C⁵, in slideways or slots c⁶ provided in the second member C⁶ of the rod which second member is provided externally with the air screw F.

In the socket formed by the member C⁶ is disposed a spring C⁷ which constantly tends to maintain the striker carrier C¹ in the position shown in the figure. It will be understood that once the expansible safety device J is disengaged a push without a movement of rotation exerted upon the member C⁶ will only produce a movement of this member by the apertures c⁶ sliding over the pins C⁵ without displacing the striker carrier proper C¹ which will continue to be wedged or locked by the balls D.

An inward movement of the striker carrier C¹ will only become possible under the effect of the push exerted by the spring C⁷ combined with the rotation of the air screw F. As in the preceding examples the operation of the firing mechanism will only take place at the end of a predetermined time, when the balls D coincide with the narrowed part C⁴ of the striker carrier C¹. The latter will then be thrown against the fixed percussion cap B by the expansion of the spring C⁷.

Other safety devices of known type may be combined with the mechanical retarding device, acting by means of a crown of balls, which forms the essential feature of the invention.

In order to prevent any untimely pressure from being exerted, by hand, upon the air screw, projections f in the form of points may, as shown in Fig. 3, be provided upon the boss of the air screw. This will be sufficient to prevent any pressure being exerted by hand upon the striker and consequently to prevent the penetration of the latter, for which penetration both of movement of rotation and a pressure are required. In other words if the air screw F is turned inadvertently by hand no inward movement of the striker will follow.

The mechanical retarding device, in all the forms of construction described, produces a suitably slowed down advance of the striker towards the percussion cap by a sort of screwing motion of very small pitch. It

is obvious that this mechanical retarding device may be employed in combination with the usual screwing means by threaded screw and nut, the special slow action screwing motion retarding device which forms the subject of the invention then only entering into action after a first displacement of the striker resulting from the screwing action obtained by means of a screw thread and nut has taken place.

Naturally, the rotating member upon which is formed one of the supports for the balls of the retarding device, instead of being the striker carrier, as in the example described, may be a percussion cap holder provided with an air screw upon an externally extending portion, the said rotary percussion cap holder being combined, if desired, with a fixed striker or with a striker carrier which is movable longitudinally.

The retarding device operating by means of a crown of balls may be applied to a protecting cover provided for the fuse, the balls being in this case interposed between convergent surfaces one of which is formed upon the fuse body and the other upon the cover, a spring being provided which can only throw off the latter after the balls have reached an enlarged portion which causes them to be disengaged from their support, or after these balls have reached the end of the fuse body, which will only take place under the combined effect of the pressure of the spring and a rotation due to the action of the air upon the fins of the cover.

Figure 10 shows in sectional elevation such a device.

The spring K located in the cover L tends constantly to eject the latter, but it can only do this if, under the combined action of the pressure of the spring and the rotation of the cover resulting from the action of the air upon the fins L¹, the balls have passed beyond the fuse body A.

The invention may be employed in firing mechanisms for marine torpedoes, in hand grenades or the like and finally in all such mechanisms in which it is of interest to retard the operation of a firing mechanism, by subordinating the latter to a combined pressure and rotation produced over a sufficiently lengthy period.

Whatever be the screwing device for the striker carrier provided with an air screw, which is employed with the movable percussion cap I, whether it is the ball device shown in Figs. 3 and 4 or other suitable device, the percussion cap instead of being fixed in the said movable percussion cap holder may itself be rendered movable in its lodgment, as shown in Fig. 11. In the lodgment I² the percussion cap will normally be retained in its forward position by a spring I³. In the event of the striker being accidentally driven in and of the failure at the same time

of the screwing device, the forcing back of the percussion cap into the lodgment I² by the point of the striker, will provide an additional safeguard.

5. What I claim is:—

1. A mechanical device for retarding and preventing the operation of projectile fuses and for other uses comprising a member to be displaced, a rotatable member, two convergent bearing surfaces, one at least of said bearing surfaces being formed on said displaceable member, one at least of said bearing surfaces being formed on said rotatable member, a crown of balls placed between

10 said convergent surfaces, one of said surfaces having a transverse enlarged space at a point in its height, said balls being adapted to exert a wedging action and retain said displaceable member, and means for giving said 15 crown of balls a combined movement of rotation and advance between said bearing surfaces causing said displaceable member and said balls to advance in a helical movement of very small pitch, said wedging action being removed when said balls enter said 20 enlarged space and escape from between said convergent surfaces.

2. In a device of the class described, a percussion cap holder, and a striker, said two 30 elements being provided with converging bearing surfaces and one of said surfaces being cut away to form an enlarged space, a crown of balls having engagement with said converging surfaces, and means for giving said crown of balls a combined movement of rotation and advance longitudinally of said 35 elements between said bearing surfaces to move said balls into said enlarged space.

3. In a device of the class described, two 40 elements adapted for relative longitudinal movement, one of which supports a percussion cap, said elements being provided with converging bearing surfaces, one of the latter being cut away to form an enlarged space, a crown of balls having engagement with said converging surfaces to prevent said 45 relative movement of said elements, and means for imparting a combined movement of rotation and advance to said balls to move the same into said enlarged space, whereby said two first named elements are adapted 50 for said relative movement.

4. In a device of the class described, two 55 elements adapted for relative longitudinal movement, one of which constitutes a percussion cap holder, said elements having converging surfaces, one of the latter being cut away to form an enlarged space, a crown of balls having engagement with said converging surfaces for locking said elements 60 against said relative movement, and an air screw for moving said balls into said enlarged space whereby said balls are moved out of locking engagement with said surfaces

and said elements are adapted for relative 65 movement.

5. In a device of the class described, a member adapted to be longitudinally displaced, a rotatable member, said members having converging bearing surfaces, a crown 70 of balls placed between said converging surfaces for normally preventing longitudinal movement of said displaceable member, and means for giving said crown of balls a combined movement of rotation and longitudinal 75 advance between said bearing surfaces to permit movement of said displaceable member.

6. A retarding device for fuses comprising, in combination with a projectile body, 80 a member carried by said body, a device adapted for longitudinal movement relative thereto in a direction to coact with said member, means including curvilinear surfaces normally locking said device against 85 said longitudinal movement relative to said member, and means for moving said device longitudinally in said direction to free the same from locking engagement with said 90 first named means.

7. A retarding device for fuses comprising, in combination with a projectile body, a member carried by said body, a device adapted to coact with said member and adapted for longitudinal movement relative 95 thereto, means normally locking said device against longitudinal movement relative to said member, and means for rotating said device and simultaneously moving the same longitudinally to free the latter from locking 100 engagement with said first named means.

8. A retarding device for fuses comprising, in combination with a projectile body, a percussion cap holder in said body, a percussion cap carried by said holder, a striker 105 adapted for longitudinal movement relative to said percussion cap, said holder and striker being provided with converging surfaces, a crown of balls engaging said surfaces, and an air propeller for rotating said 110 crown of balls and simultaneously moving the same longitudinally.

9. A device of the class described comprising, in combination with a projectile body, a holder movably mounted in said body, a 115 percussion cap carried by said holder, striker means associated with said holder, said striker and holder having converging surfaces, one of said surfaces being cut away to form a lodgment, a striker extending into 120 said holder, means engaging said converging surfaces for preventing relative longitudinal movement between said striker and percussion cap, and means for moving said first named means into said lodgment.

10. A device of the class described comprising, in combination with a projectile body, a holder movably mounted in said

- body, a percussion cap carried by said holder, striker means associated with said holder, said striker and holder having converging surfaces, one of said surfaces being cut away
5 to form a lodgment, a striker extending into said holder, means engaging said converging surfaces for preventing relative longitudinal movement between said striker and percussion cap, means for moving said first named
10 means into said lodgment, and pin and slot means operatively connecting said holder and fuse body.
11. A device of the class described comprising, in combination with a projectile body, a holder movably mounted in said

body, a percussion cap carried by said holder, striker means associated with said holder, said striker and holder having converging surfaces, one of said surfaces being cut away 20 to form a lodgment, a striker extending into said holder, means engaging said converging surfaces for preventing relative longitudinal movement between said striker and percussion cap, means for moving said first named means into said lodgment, and resilient 25 means for resisting movement of the holder relative to the projectile body.

In testimony whereof I have signed this specification.

LÉON ÉMILE RÉMONDY.
